UNITED STATES PATENT OFFICE

FRITZ ALDENDORFF, OF BERLIN, GERMANY; CHARLOTTE ALDENDORFF HEIRESS OF
SAID FRITZ ALDENDORFF, DECEASEDELECTROMECHANICALLY-CONTROLLED SWITCH AND REMOTE-CONTROL SIGNALING
AND TELEPHONE SYSTEM

Application filed January 20, 1927, Serial No. 162,399, and in Great Britain January 19, 1926.

This invention relates in general to electro-mechanically controlled systems and more particularly to telephone systems of the kind in which switches are employed whose 5 brushes are moved by power, which may be supplied by a spring, the brush movements being controlled by a toothed wheel attached to the brush shaft and an electromagnet armature which alternately releases and stops 10 the wheel so that the brushes execute steps which may be of different lengths. Apparatus of this character is also capable of application for mine signaling and the control of electric machinery in automatic sub-stations. So far, however, I have developed the 15 invention particularly for telephony and this specification is mainly concerned with such developments.

In quick-acting switches of the kind referred to it is essential that the control means for starting and stopping the switches should be reliable and the more reliable the control means can be made the quicker can be the speed of operation permitted.

The present invention comprises improved 25 means of control some of a mechanical nature and some electrical. In order to provide for accurate adjustment of the switch stopping member the pawl or braking member is made adjustable on the armature of the starting and stopping magnet. In order to avoid the necessity of restoring the potential energy of spring operated switches, an 35 electric torque producer, such as an electric alternating current or direct current motor may be employed on each brush carrying shaft. In some cases an electrically rotated shaft may supply power to a number of switches and electric coupling means may be 40 provided individually to each brush carrying shaft.

The improved switch of this invention, without altering the mechanical construction, may be so arranged in connection with electric operating circuits that it works as desired as line-finder, pre-selector, distributing switch with very many outlets, group selector or connector.

The new switch has on its brush spindle a 50 wheel with teeth corresponding with the bank

contacts. The wheel is driven together with the brush spindle by a separate driving means, which may be a spring or electric motor or the like, and is stopped at the right point by means of a pawl. The adjustment 55 of the brushes in relation to the bank contacts and the adjustment of the stopping pawl in relation to the teeth of the wheel is such that the point of the pawl, at the moment when the brush just leaves the bank contact located in front of the desired bank contact, stands in front of a tooth of the stopping wheel so that substantially the whole time 60 which the brush requires to pass over the air gap separating the desired bank contact from the adjacent bank contacts is obtained for the falling in of the stopping pawl into the correct slot between the teeth. Preferably the 65 adjustment is such that the switch controlling brush to which a brush controlling magnet is connected is only stopped by the striking of a tooth of said wheel against the stopping pawl when the narrow contacting surface of said brush has travelled at least five-eights 70 of the distance between the two bank contacts between which the desired bank contact is located. The bank contacts are embedded in a carrier or carriers of a pressed material and these carriers can be adjusted for the purpose 75 of the coarse adjustment of the circle of contacts in relation to the selector shaft. For accelerating the falling in of the stopping pawl into the wheel, a condenser reacting on the magnet winding of the control magnet is 80 provided which is connected preferably parallel to the magnet. The retraction of the stopping magnet armature can be accelerated by making the magnetic flux path of this magnet of nickel iron. The switch is further 85 characterized by a control magnet, whose armature responds to absence of current at high brush speed, and a relay, which does not respond when the brushes connected with it 90 pass over contacts connected to battery until the selector brushes are positively stopped by the armature of the control magnet.

In order to improve the controlling means by which the brushes of such switches are stopped at desired points of the contact bank, 95 there are provided both at the beginning and 100

middle of each long step around the contact bank with a set of indicating contacts that mark the positions where the brushes are to be arrested, and with circuit arrangements for applying potential to said sets of indicating contacts alternately in accordance with dialling impulses sent to the switch whereby the brushes are liberated so that they execute long steps, and with further circuit arrangements by which said electromagnet receives an impulse to cause it to allow the brushes to move to the last contact of a set of indicating contacts located at the beginning of a long step whenever they have been stopped on a contact located before the last one of a set at the end of a dialling operation.

According to the invention, the brush carrier may be driven by an electric torque producer such as an electric motor individual to the switch. The motor is stopped in a position effecting the desired connection by means of a stopping pawl, which engages in a toothed wheel connected to the brush carrier when the brushes reach a set of contacts on which it is desired that they should stop. Alternatively the brush carrier may be stopped by means of a friction brake which comes into operation at the desired moment. At the same time or substantially so the electric supply to the motor is disconnected. The arrangement may be such that so long as the brushes are sliding over bank contacts to which potential is not applied, the stopping pawl is held away from the toothed wheel by means of an electromagnet which is deenergized for the purpose of stopping the brushes as soon as a brush, closing the circuit of the electromagnet, reaches a marked contact.

A feature of the invention consists in making the test bank contacts of a switch connected to the individual lines have a longer wiping surface than the talking contacts.

The electrically driven switch, according to the invention, can be operated as a line finder, preselector, trunk finder, group selector and connector. When used as a group selector, the hunting operation for finding a free trunk is initiated through the contacts of a relay whose one winding is short-circuited as long as the hunting operation lasts and after a free line has been found owing to change over of contacts, the connection is put through to the next switch. The arrangement is such that the hunting operation ceases in any case when the brushes have hunted over all the lines existing in the group.

When used as a connector, the switch brushes are propelled from contact to contact by applying an electric potential to the bank contacts in succession by means of a relay. This relay, which applies the potential alternately to different individual bank

contacts, is also used for preparing the test circuit.

When using the switch as numerical impulse receiver, the circuit arrangement is such that after the seizure of the switch by a calling line, always at least one opening and one closing of the line extending towards the calling station is required for the movement of the selector brushes. The first current impulse affecting the brushes of the switch, given off by the current impulse relay, originates after the first drop of the armature and subsequent armature attraction of the current impulse relay. This current impulse is taken through working contacts of the current impulse relay and the change-over relay.

One arrangement of electric drive comprises a motor which is practically uncoupled from the selector shaft at the moment when it is started and is coupled to the selector shaft after it has executed some motion, for example, half a revolution or more. At the moment when the motor is coupled a resistance or resistances are connected in the motor circuit to reduce its torque. These resistances may be placed in series with the motor, that is in the leads to the motor or in the armatures, windings or in any other convenient manner.

The brush shaft may be driven by a driving device associated with the switch by means of friction coupling and positively stopped in the desired position by means of a locking arrangement. The driving device then appropriately consists of a separate electric torque producer associated with the switch. It may, however, also consist of a disc or the like secured on a continuously rotating shaft capable of being magnetized at suitable moments and a ring or the like mounted on the switch shaft which is attracted by the disc. The coupling between the torque producer or motor and the switch shaft is preferably constructed in the form of two plates drawn or pressed together which embrace a ring or the like secured on the switch shaft. The switch shaft and the shaft of the driving device may be arranged parallel to one another. In another constructional form, the switch shaft and the switch of the driving device extend at right angles or at some other angle to one another. The switch shaft is driven with such speed that the brushes, when numerical impulses are sent by means of an impulse transmitter of the usual kind, jump between two successive current impulses always over a whole group of contact sets and the first half of this group is jumped over at the opening of the line group and the second half of the group on the closing of the line group extending towards the calling subscriber.

The positive locking or stopping of the contact brushes at the desired position of the contact

bank is effected by a toothed wheel mounted on the brush carrier and a stopping pawl engaging in the toothed wheel.

One feature of the invention is a power driven switch provided with a brush carrier that, when started, is driven forward until a brush reaches a waiting line and is arrested after use by a positively acting arresting member, said member being made to release the brush carrier to enable it to be driven forward again if the brush should fail to stop during its first movement on a waiting line. Another feature of the invention consists in a switch provided with a spring 10 driven brush carrying shaft, a spring re-winding shaft to which rotary motion is imparted by an electromagnetic device whose power is made effective, when the brushes of the brush carrying shaft have trailed over all of their bank contacts, by contacts closed by a member attached to the latter shaft, these contacts being opened when the brush driving spring is rewound. A further feature of the invention consists in a power 20 driven switch whose brushes are stopped in any desired position by a positively acting electromechanically controlled member that cooperates with the brush carrier, a speed regulator being provided for regulating the speed at which the brushes pass over the bank contacts of the switch. Another feature of the invention comprises a switch having a brush carrier with an electric driving motor individual thereto, a toothed wheel that is 30 stopped on the mechanical detent when the brushes reach a desired position and contacts for disconnecting the current supply to the motor when the brushes are stopped.

A further feature of the invention consists in a remote control switching system provided with line finders which respond in succession to effect connections with waiting lines and means by which, when a line finder fails to connect a waiting line through to a connecting line or trunk within a certain time, the waiting line causes the next idle finder to operate to connect the line to a trunk, switch or the like. Another feature of the invention comprises a remote control switching arm in which a switch is provided with a plurality of sets of selectively operable brushes mounted on one and the same brush carrier and in which there are means by which one or another set of brushes are 40 made to effect a connection according to the first signal or series of selecting impulses sent from the calling station to the switch denotes the said one or another set of brushes. Another feature of the invention comprises 50 an electromechanically controlled telephone system provided with a ringing cut-off and through-connecting relay over whose bank contacts ringing current and a relay-energizing battery are applied alternately through 60 the brushes of a signal current switch to a

wanted line. The signal current switch may be arranged so that, when a line makes a call, current impulses are sent from the switch at certain intervals to the operating magnet of a trunk finder for the purpose of shifting the trunk finder brushes from a faulty trunk to a good one. 70

Referring to the accompanying drawings:

Figure 1 is a diagrammatic perspective view of a spring driven switch which may be used with the circuits shown in Figure 2 as a line finder. 75

Figure 2 shows the circuits of a line finder and Figure 3 the circuits of a connector according to the invention provided with a plurality of sets of brushes. 80

Figure 4 is a perspective view partly in section showing the switch when spring driven.

Figure 5 is a diagrammatic perspective view of a motor driven switch, Figure 6 shows a view of a switch according to the invention in which the brush shaft is driven by a motor whose shaft extends parallel to the brush shaft. Figure 7 shows a switch in which the brush shaft extends at right angles to the motor shaft. Figure 8 shows a switch whose brush shaft is driven by a continuously rotating driving shaft by means of friction coupling. 90

Figure 9 is a front view of bank contacts and a double brush which slides over these contacts. Figure 10 is a side view of the end of a motor adjacent to the driven end of a switch, Figure 11 is a view of Figure 10 as seen from the right and Figure 12 is a circuit diagram of the motor and of parts of a switch driven by the motor. Figure 13 shows a subscriber's station, two line finders working in series and four trunk finders. Figure 14 shows the circuit arrangement of a group selector and Figure 15 the circuit arrangement of a connector. 95

Referring now to the drawings the switch shown in Figure 1 comprises a central brush-carrying shaft 1 to which is fixed a toothed brush-arresting wheel 2, a worm wheel 3 and a notched disc 4. Arranged to rotate around the central shaft 1 is a hollow-shaft 5 to which is fixed a spring-rewinding wheel 6, a notched disc 7, a spring box 8 and a cam 9. 100 The spring box 8 contains a spring whose outer end is attached to the peripheral wall of the spring box and whose inner end is fixed to the central shaft 1. When the central shaft 1 is held against rotation, as by a detent 10, and the hollow-shaft 5 with the spring box 8 is rotated by the pawl of a spring-winding magnet 11 that cooperates with the wheel 6, a torque is applied to the central shaft so that when it is released by the 105 detent 10 being attracted by the magnet 12 the shaft 1 with the brushes 13, 14, 15, 16 is whirled round. The current through the magnet 12 flows through a hunting brush 16 and through bank contacts until the desired 110 115 120 125 130

set of bank contacts is reached, when the magnet 12 is deenergized and the brushes are stopped by the detent 10 being jerked by a spring 17 into engagement with the toothed arresting wheel 2.

5 It must be noted that when the brushes 13 to 16 are in their normal position the arresting member 18 is lifted clear of the rotary stop 19 on the wheel to allow the stop 19 to pass.

10 The moment the central shaft 1 is rotated out of its normal position the disc 4 closes a pair of contact springs 20 and when the hollow shaft 5 is rotated out of its normal position its disc 7 closes a pair of contact springs 21. At the end of a connection through the switch the central shaft is released and a projection 22 is then rotated further, i. e. in the direction of the arrow, 15 into its home position in which it pushes a contact spring 23 forward into contact with a spring 24 and thus closes, in a manner to be more fully described with reference to Figure 3, a circuit through the rewinding 20 magnet 11 which now rotates the hollow shaft until the contacts 23, 24 are opened through the agency of a cam 26 that turns a bell crank lever 25 which in turn raises the contact spring 23 out of the path of 25 the projection 22 so that the latter moves forward to the front of the spring 23 as shown in Figure 1. In this position spring 23 is out of contact with spring 24 and then, or if the projection 26 is placed so as 30 to throw the lever 25 before the hollow shaft is restored to normal, afterwards when the contact springs 21 are opened, the rewinding circuit through the magnet 11 is broken. All parts of the switch have then 35 returned to their normal position. Short- 40 ly before the hollow shaft is stopped in its normal position the cam 9 lifts the arresting member 18 out of the path of rotating stop 19 which by striking against 18 stops the central shaft 1 in its normal position in 45 the restoring operation. The central shaft 1 is rotated at a high speed which is governed by a speed regulator whose shaft 28 is driven by the worm wheel 3 and worm 27. At- 50 tached to the shaft 28 are two springs 29, 30 loaded at their ends by weights or friction members 32, 33 that rub against the internal periphery of a casing 34. The degree of friction, and thus the speed, can be 55 regulated by varying the resiliency of the springs 29, 30 by means of an adjustable ring 31 that can be slipped along the shaft to vary the active length of said springs. The regulator is a considerable aid in ad- 60 justing the switch to operate at a high speed but not too high to prevent proper stopping of the brushes 13 to 16 on any desired bank contact set. If the brushes should by any chance not be properly stopped on the 65 bank contacts of a waiting line in their first

rotation the projection 22 will close the spring contacts 23, 24 and this results in the rewinding of the brush driving spring and the unlocking of the detent 18 so that the brushes will be whirled around a second time. This time the spring power will be small and the brush will be rotated more slowly.

70 In Figure 2, LF is a line finder of the type shown in Figure 1. TF is a trunk finder adapted to preselect a free trunk or line finder LF and to start the latter when a call is made by a line connected to the bank contacts of the line finders. In Figure 3, C is a connector with two sets of brushes mounted on a common shaft that is rotated by a stepping magnet M_3 . SS is a slow signal-current switch, which when a line calls, is started for the purpose of sending impulses to the trunk finder TF to shift its brushes onto another trunk in case the trunk the brushes are resting on is not connected through the waiting or calling line within a certain short time. The switch SS also intermittently connects ringing current to wanted lines. The circuits in Figures 2 and 3 will now be more fully described.

75 It will be assumed that a calling station CS desires a connection with a line No. 14.

80 When the receiver at the calling station is raised the line relay 40 is energized and at its contact 41 disconnects the positive pole from the marking contact 42 of the line finder LF. At 42' a circuit is closed through the brush 43 of the trunk finder and the finder starting relay 44. The latter relay at its contact 45 closes the circuit of the starting and stopping magnet 12 which corresponds to the magnet 12 in Figure 1. The circuit through the magnet 12 extends from the negative pole through contact 45, contact 46 of the through-connecting relay 47, brush 48, a contact similar to 42 on which the brush 48 rests in its normal position, a contact similar to contact 41 of a line relay to the positive pole. The brushes 48, 49, 50, 51, of the line finder are now whirled round until the brush 48 reaches a contact such as 42 that is disconnected from the positive pole. At this moment the arresting pawl 10, Figure 1, stops the brushes and the relay 47 is energized by a current flowing from the negative pole through contacts 52, 47, brush 49 contact 53 of the line relay 40, cut-off relay 54 to the positive pole of the battery. The relay 54 closes a contact 55 and thus makes the circuit through itself and through the relay 47 independent of the contact 53 which is opened when the relay 54 is energized, because hereby the line relay 40 is disconnected and de-energized. The relay 47 connects the calling line through contacts 56, 57 to the impulse relay 100 of the connector C and this relay is then energized by current flowing to the 90 95 100 105 110 115 120 125 130

waiting station. At its contact 101 the impulse relay closes a circuit for the release relay 102, which circuit extends from the negative pole through 102, resistance 103, to the positive pole. The moment the release relay 102 is energized, it establishes a locking circuit for itself at contacts 104, a new circuit for the relay 47 at contact 105 and a shifting circuit for the trunk finder TF at contact 106. 5 The magnet 60 of the trunk finder is then energized by current flowing through its bank contacts 61, brush 62, 60 to the negative interrupter. The brushes 43, 62, 63 of the trunk finder are now stepped down until the 10 brush 62 reaches a contact like 61 that is not connected through a contact like 106 to the positive pole.

The described operation of connecting a calling line through the line finder to the 20 impulse relay 100 associated with its trunk should normally take place in a fraction of a second. If this through-connecting operation is not executed within a certain time after the energization of the line relay 40, 25 the brushes of the trunk finder TF will be shifted to another trunk by a safety device that comprises relays 64, 65 and certain contacts on the slowly stepping signaling switch SS'. When the relay 64 is energized 30 it closes a circuit that extends from the negative pole through 69, oscillating member St of a slow-acting interrupter, winding 107 of the slow interrupter to the positive pole. The slow interrupter has an armature 108 35 which on its attraction by the winding 107 flings round the arm 109, this arm 109 is caused to swing back rather slowly to re-establish a contact at 111. By this means slowly recurring impulses are sent through the 40 stepping magnet 112 of the signal switch which steps its brushes 113, 114, 115, 116 from contact set to contact set. When the brush 116 reaches the bank contact 117, the relay 65 is energized and closes a locking circuit 45 for itself at its contact 118. When the brush 116 reaches contact 119 a current impulse is sent to the operating magnet 60 of the trunk finder in a circuit which extends from the positive pole through 118, brush 50 116, contact 119, wire 121, contact 122, brush 63, magnet 60 to the negative pole. The magnet 60 then steps the brushes of the trunk finder onto the bank contact set of another trunk and an impulse then flows from 55 the positive pole through contact 42', brush 43 of the trunk finder to a starting relay like 44 of the next idle trunk. This causes the line finder of that particular trunk to be started and to connect the waiting line to an 60 idle trunk or link. The moment the waiting line is connected through the line relay 40 is deenergized and this in turn causes the de-energization of the relays 64 and 65 and also the stoppage of the signal switch SS. 65 If a trunk belonging to a bank contact 70 or

72 of the trunk finder is faulty an impulse will within a certain period be sent from the signal switch SS over wire 123, contact 124 or 125, brush 63 to the magnet 60 of the trunk finder to step the latter on to another 70 trunk.

If during its first rotation the line finder should operate at too high a speed to enable the arresting pawl of the arresting magnet 12 to stop the brushes on the proper line, the 75 projection 22 attached to the disc 4, (see also Figure 1,) will be whirled completely around and will press the contact spring 23 against spring 24 so as to close the circuit of the rewinding magnet 11. This circuit extends from the positive pole through 11, 24, 23, wire 80, winding 81 to the negative pole. The relay 81 is energized and at contact 82 short-circuits itself and thus causes the magnet 11 to respond. Immediately afterwards the relay 81 allows its armature to drop back so as to weaken the current in the rewinding magnet 11 sufficiently to cause it to deenergize. The oscillations of the armature of the relay 81 thus cause stepping impulses to flow 85 through the rewinding magnet 11. The magnet 11 steps the hollow shaft and the notched disc 7 around and after it has turned through a certain angle a projection 26 attached to it causes the contacts 23, 24 to be opened. The 90 cam 9 on the hollow shaft raises the detent 18 to unlock the brush carrying shaft so that this brush will again be whirled round. This time, due to the spring being partially unwound, the brushes will travel at a somewhat lower speed at which the arresting detent of the magnet 12 will be sure to stop the brushes on the proper line. The rewinding magnet 11 continues to receive rewinding impulses until the disc 7 has executed a complete revolution when the contact springs 21 will be opened so as to break the rewinding circuit 95 through the magnet 11.

Assuming that the calling subscriber has been connected through to the impulse relay 100 and that the release relay 102 has been energized as described, the slow interrupter SI will be started by a circuit extending from the negative pole through contact 104, contact 130, 109, 111, 107 to the positive pole. The signal switch SS is thus started for the purpose of sending out ringing current at the proper moment that is when the brushes of the connector C have been stepped on to a wanted idle line. The calling station now 110 works the dial and thus gives rise to one interruption of the current in the impulse relay 100 and a stepping impulse flows from the negative pole through contact 104, contact 131 of impulse relay, stepping magnet M_3 , 115 to the positive pole. A pause now ensues before the unit selecting impulses are sent and during this pause the change-over relay 132 which was energized when the armature of the impulse relay dropped back and opened 120 125 130

the short-circuit of the relay 132, closes at its contact 133 a circuit that extends through contact 134, brush-changing relay 136 to the positive pole. This circuit can only be closed 5 when the brush carrying shaft has been made to execute a single step so as to cause the cam 135 to close the contact 134. If two tens impulses are sent through the impulse relay 100, the cam 135 will pass beyond the contact springs 134 and a change-over action 10 that takes place after the tens impulses have been sent will then fail to close a circuit through 133, 134 and the brush-changing relay 136 so that the brushes 137, 138, 139 will remain connected to the trunk instead of the 15 brushes 140, 141, 142 being connected thereto.

Assuming that the brush-changing relay 136 has been energized as described, this relay closes at its contact 143 a locking circuit for 20 itself that extends through contact 104 to the negative pole. When the units impulses are now sent in the stepping magnet M_3 receives impulses as before in a circuit extending from the negative pole through 105, contact 131, magnet M_3 to the positive pole. This steps 25 the brushes 140, 141, 142 on to the bank contacts of line 14. When the units impulses cease, the change-over relay 132 allows its armature to drop back and, if the wanted line 30 is free, the test relay is now energized in a circuit extending from the negative pole through 104, contact 133', test relay 150, contact 151, test brush 142, test wire 151, contact like 152 on the line relay of the wanted line, cut-off relay like 54 to the positive pole. 35 When the test relay is thus energized it short-circuits a part of its winding through contact 154 and thus reduces the potential on the multiple test bank contacts of the connectors so as to render the wanted line busy. At its contacts 155, 156 a circuit is now closed for intermittent ringing current which flows through brushes 113, 114, wires 157, 158, contacts 159, 160 on a through-connecting and ringing cut-off relay 161. In the intervals between the 40 ringing current impulses, a negative battery pole is connected by brush 115 to the wire 162 and through this wire and contact 163 to the lower winding of the relay 161. When the wanted subscriber responds continuous current flows through the windings of the relay 161 and this relay is then energized to close contacts 164 and 165, 166, 167. The relay 161 locks itself through contact 166 until a wanted subscriber replaces his receiver. At contact 45 167, the relay 161 closes the circuit of an auxiliary release relay 168 which latter relay opens the circuit of the slow interrupter at contact 130 and closes a locking circuit for itself at contact 169.

50 When the wanted subscriber replaces his receiver, the connector C is restored to normal by impulses that flow through the magnet M_3 in a circuit extending from the positive pole through M_3 , contact 171, contact 172, contact 173 to the impulser 81. When the

brushes reach their normal position, this restoring circuit is opened by the off-normal contact 173. When the calling subscriber replaces his receiver the circuit of the relay 47 which produces the busy condition of the calling line is opened at contact 105 and at contact 46 the magnet 12 of line finder is then energized in a circuit extending from the negative pole through 12, contacts 20, contact 46, brush 48, contact 42, contact 41 of the line relay to the positive pole. The arresting detent is thus disengaged from the arresting wheel, see Figure 1, of the brush carrying shaft and this shaft is restored to its normal position until the projection 22 pushes the spring 23 against spring 24 so as to close the rewinding circuit through rewinding magnet 11 which now rewinds the spring in the manner already described.

55 If the calling subscriber replaces his receiver first, the connector C is restored to normal by restoring impulses flowing from the positive pole through the magnet M_3 , contact 190 of the restoring relay, off-normal contacts 173 to the impulser 81.

Referring now to Figure 4, the switch has a shaft 1 on which the brushes are secured in an insulated manner, only the brush 2 being shown. In the shaft 1, mounted to rotate thereon, is a hollow shaft 5 which carries at its upper end a gear wheel 6 and at the lower end a spring-box 7. The one end of the spring 8 is connected with the shaft 1 and the other end with the casing of the spring-box 7, so that when the spring box is rotated in the direction of the arrow, the spring 8 tends also to rotate the brush shaft in the same direction. The rotation of the spring box and consequently also the tensioning of the spring is effected by means of a propelling pawl 10, which is made to vibrate by an electromagnet 5 which rotates step-by-step a toothed wheel 6 connected with the spring box. Return rotations of the wheel 6 are prevented by a locking pawl 9. The brush shaft 1 is held against the action of the spring 8 by means of a stopping pawl 4 which engages in the teeth of a wheel 3 secured on the shaft 1. In order to stop the brushes 11 on any bank contact the stopping pawl 4 is lifted out of the wheel 3 by excitation of the control magnet 11 and as soon as the brush leaves the bank contact located in front of the desired bank contact the magnet 11 is again deenergized so that the pawl again engages the wheel 3 and stops it. The exciting current of the magnet 11 flows through the brush 12 and the bank contacts wiped by it. All the bank contacts except, for example, 15, where the brush is to stop, are connected with the 115 battery. The adjustment of the brush 12 in relation to the bank contacts and the adjustment of the stopping pawl 4 in relation to the teeth of the wheel 3, the stopping pawl being 120 adjustable on the armature lever 20, is such 125

that the point of the pawl 4 at the moment when the brush 12 just leaves the bank contact 14 lying in front of the desired bank contact 15, stands in front of a tip of a tooth 5 of the locking wheel 3 so that the entire time which the brush 12 needs in order to pass over to the desired bank contact 15 and over the air gap 17 separating the adjacent bank contacts 14, 15 is obtained for the falling of 10 the stopping pawl 4 into the correct tooth gap. The slotted pawl 4 is screwed fast by screws 4' on the armature lever 20 and secured against displacement by means of a screw 4'' adjustable in a screw-threaded 15 aperture of the bent up end of the armature lever 20. Appropriately also a security nut is provided. The time of dropping in of the pawl 4 can be adjusted by regulation of the tension of the armature return spring 19. An 20 important means for shortening the time of falling of the armature 20 and for the rapid engagement of the stopping pawl 4 in the correct tooth gap, is the condenser C reacting on the magnet coil 11, the condenser may be 25 connected parallel to the coil 11. By means of the condenser C the result is obtained that the current in the coil 11 when its circuit is opened not only closes more quickly but to a certain extent reverses its direction. By this 30 means the residual magnetism of the control magnet core is opposed. It has been found in practice that the selector will stop its brushes with sufficient certainty when it wipes over its bank contacts with a speed of 35 300 contacts per second. A 100 point line-finder of this construction, therefore, reaches the hundredth bank contact lying furthest away from the normal position of the brushes in one third of a second so that the use of a 40 dialling tone which indicates to a calling subscriber that his line is connected to the next selector and consequently he can operate his dial is dispensed with.

The switch shown in Figure 5, has a brush 45 carrier or a brush shaft 1 on which the brushes 2', 3', 4', 5' are secured in an insulated manner. The shaft also carries a toothed wheel 6, the armature 7' of an electric torque producer or electric motor 9' and 50 a worm wheel 8'' which engages in a worm 10' of a speed regulator 10'.

The operation of the switch is such that as soon as the brushes are to be set on any particular contact or shortly beforehand, the 55 electric motor 9' is switched in and then the magnet 11 withdraws the stopping pawl 12' from the stopping wheel 6. The brush carrier 1 is whirled round with high speed, which is regulated by regulator 10'', until 60 the test brush 5' reaches the one dead test contact, for example, 13', when the circuit of the electromagnet 11 is broken. The electromagnet 11 is then rapidly deenergized and the stopping pawl 12 falls into engagement 65 with the stopping wheel 6 and holds

the brush carrier 1 fast. Simultaneously or shortly thereafter, the electric motor 9' is disconnected. In order to obtain an exact operation of the stopping pawl 12, the test bank contacts 13' are made longer than the 70 talking contacts 14', so that in the transfer of the test brushes 5 from one contact to the next, an interruption of the current flowing through the brush 5 only takes place when this brush reaches a dead test contact. 75

The switch shown in Figure 6 has a brush shaft 1 which is mounted in bearings 2', 3'. On the shaft are secured with insulation, brushes 2, 3, 4, 5 which wipe over bank contacts 13, 14 when the shaft 1 is rotated. On the shaft 1 is further secured a stopping wheel 6 in which the stopping pawl of the armature 12 of a magnet 11 engages. On the wheel 6 is secured a ring 4' which has a ring surface 5¹¹ extending inwards. The ring surface 5¹¹ is embraced by two plates 7', 8' pressed against one another which constitute the driving wheel of an electric motor 9. When the switch is set into operation, the motor 9 is switched in and simultaneously or a little later, the electromagnet 11 is excited which then lifts the stopping pawl 6 out of the stopping wheel 6 and liberates the brush shaft 1. The magnet 11 is kept excited by a current which flows through the brush 5 and bank contacts 13 until a contact 13 is reached which is disconnected from battery. At that moment the current through the electromagnet 11 and the brush 5 is interrupted and the armature 12 is brought 90 back into its normal position by a spring when the stopping pawl engages in the stopping wheel 6 and thereby stops the brush shaft. The brush 5 is constructed as a double brush and in the passage of the brush from one bank contact 13 to the next, the one brush half 5 leaves the next contact 13 before the other brush half 5² leaves the preceding bank contact 13. This feature, of 95 course, is also applicable to the spring driven switch. The adjustment of the stopping pawl is such that the brush 5 has always wiped over the greatest part of a bank contact 13 before the corresponding teeth of the stopping wheel 6 abuts against the stopping pawl. By this means the greatest possible 100 time of falling for the armature 12 of the switch is obtained. 105

The details of the switch shown in Figure 12 corresponds to those of Figures 11, 14 and 15 with the exception that the motor shaft extends at a right angle to the brush shaft. If necessary, the motor and brush shaft may be at an angle to one another other than a right angle. In Figure 12 the two elastic 115 plates 7', 8' which are pressed against one another by the nut, embrace a ring 4² projecting downwards secured on the stopping wheel 6 and thereby driving the brush shaft. 120

In the switch shown in Figure 13, the 125

brush shaft 1 is provided with an elastic disc 12^a which carries an iron ring 4^a. On a continuously rotating shaft 11^a, is secured an iron disc 7^a which for the purpose of setting the switch into operation is magnetized by a 5 coil 9^a. When the disc 7^a is magnetized or immediately thereafter, the starting and stopping magnet 11 is excited and the disc 7^a then drives the brush shaft 1 by means of 10 the ring 4^a. The brush shaft may be provided with a speed regulator like 10" in Figure 10.

In Figure 16 *a* represents a fragment of the motor field magnet which is built up of thin iron sheets. *b* is a field winding and *c* is a bearing in which the motor shaft *d* that carries a disc *e* is journalled. Projecting from the disc *e* is a pin *f* and a finger *g*. Fixed on the disc *e* are also resistances *h*, *i* and contact 15 springs *j*, *l* and *m*, *n*. Protruding through the finger *g* is a stud *o* of insulating material. *l* is one end of the switch shaft on which is fixed a carrier member *o*¹. Normally a spring *p* which is shown by a broken line in Figure 20 16 only, turns the disc *e* and the armature of the motor so that the pin *f* rests against the top end of the carrier arm *o*. When the motor is switched on, its armature turns its shaft *d* and its disc *e* in the direction of the arrow and 25 the only mechanical resistance that the armature has to overcome initially is that of the weak spring *p*. After the armature has executed slightly more than half a revolution, the stud *o* and immediately thereafter, the 30 finger *g* strikes against the upper end of the arm *o* and commences rotating the shaft 1 of the switch. The stud *o* is forced back in the hole in finger *g* and the contacts *j*, *l* and *m*, *n* are opened, whereby resistances *h*, *i* are 35 inserted in the armature winding and the torque of the armature is reduced, (see Figure 18) in which 11 represents the controlling magnet of the switch driven by the motor, 5¹ is the selector brush that cooperates with 40 the stopping magnet 11. 13¹ are bank contacts and 12 the stopping pawl which cooperates with the brush stopping wheel 6. C is a condenser which is connected in parallel with the brush 5¹. It accelerates the dropping back 45 of the armature 12 of the selector controlling magnet 11 when the brush 5¹ reaches a bank contact, which is devoid of potential.

The resistance or resistances *h*, *i* could be placed outside the motor, but then it would 55 be necessary to arrange slip contact rings and corresponding brushes on the motor or selector shaft. With the arrangement shown in Figures 16 and 17, the blow delivered against the stud *o* when it strikes against the carrier 60 arm *o*¹ results in a sudden and wide opening of the contacts *j*, *l* and *m*, *n* and this reduces sparking at these contacts.

Referring to Figures 19 to 21, the circuit operations will now be explained which take 65 place in making a connection with wanted

subscriber No. 223. When the calling subscriber S takes down his receiver from the hook, a current flows from the positive pole through the line relay 20, contact 21 of the cut-off relay 22, telephone instrument S, contact 22 of the cut-off relay 23 to the negative pole. The relay 20 connects by means of the contact 24, the cut-off relay 23 with the bank contact 25 of a first line finder LF¹; at the contact 26 it closes through a resistance 27, 70 the circuit of a stepping relay 28 and at the contact 29 it cuts off the positive pole from the marking bank contact 30. The stepping relay receives through the resistance 27, sufficient current to close its contacts 31, 32 whilst 75 the contacts 33, 34 are only closed when a second subscriber calls and connects the positive pole through the corresponding line relay 35 and a further resistance 36 with the starting line 37. Through the closure of the 80 contact 31, the first line finder LF¹ is started and through the closure of the contact 32, the second line finder LF² is started in connection with which it should be observed that the trunk finders TF¹ and TF² have already 85 set their brushes previously on free trunks in a manner to be described later.

The starting magnet 11¹ of the line finder LF¹ receives current which flows from the negative pole through 11¹, contact 38, line 39, brush 40, contact 31, brush 42, a contact corresponding to the contact 29 of a non-calling subscriber or other subscriber to the positive pole. The stopping magnet 11¹ closes at its contact 43 a circuit independent of the contacts 38 and 31; at the contact 44 it prepares a circuit for the through-connecting relay 45. At the contact 46 it closes an exciting circuit for a relay 47 and at the contact 48 it switches in the motor 9¹. Since the magnet 11¹ simultaneously draws out the stopping pawl from the stopping wheel (see 6, Figure 10) the motor 9¹ now whirls the brushes 42, 49, 50, 51 round with high speed until the brush 42 reaches contact 30 through which the positive pole is disconnected. At this moment, the magnet 11¹ is deprived of current, the stopping pawl falls into engagement with the stopping wheel and holds the brushes 42, 49, 50, 51 fast. At the contact 49 the circuit of the magnet 11¹ is again interrupted whilst at the contacts 46, 48, the slow-acting relay 47 and the motor 9¹ are disconnected. Through the contact 44 of the slow-dropping relay 47, however, the through-connecting relay 45 is excited in a circuit which extends from the negative pole through 44, 45, 49, 25, 24, cut-off relay 23 to the positive pole. Relay 45 connects the brushes 51, 50 through the contacts 52, 53 to the bank contacts of the second line finder LF². After its excitation the relay 45 also receives current through the upper low resistance winding of the relay 47, contact 54, contact 55, low resistance winding of 45, brush 49, contact 55 of the cut-off relay 23 110

which has in the meantime responded to the positive pole. By means of the circuit just described, the potential on the test line 57 leading to the connectors is lowered to such an extent that the calling line continues to appear engaged. The relay 47 at the contact 58 cuts off the positive pole from the marking contact 101 of the second line finder LF^2 and at the contact 59 it closes a circuit for the test relay 60 and the driving magnet 61 of the trunk finder TF^1 . The magnet 61 is excited by current impulses which extend from the negative pole through 59, brushes 62, 61, interrupter 63 to the positive pole. So long as the brushes of the trunk finder TF^1 reach engaged trunks, the magnet 61 receives negative impulses through contacts which correspond to the contact 59 of a relay 47 or the contact 64 of a relay 45 so that the brushes are continuously carried through. Furthermore, so long as the brushes of the trunk finder reach lines which are already engaged by another trunk finder, the magnet 61 receives negative impulses which extend through a contact 66, brush 68 of another finder, 67, brush 65, contact 68, magnet 61, interrupter 63 to the positive pole. So soon, however, as the brushes of the trunk finder TF^1 reach a line which is not engaged and is not taken by another trunk finder, the circuit of the magnet 61 and of the relay 60 is broken and the brushes remain stationary on the particular trunk. The contact 69 of the relay 60 then marks the trunk reached as engaged so that another trunk finder will not remain on this line.

If the second line finder LF^2 does not already stand on the trunk belonging to the line finder LF^1 , its starting magnet 112 is excited by a current which flows from the negative pole through 112, line 102, line 119, brush 104, contact 32 of the stepping relay 28, brush 105, line 106, 107, brush 108, contact like 101, a contact like 58, which at this moment is closed, to the positive pole. The magnet 112 closes at the contact 113, the circuit of the motor 19 and at the contact 114 it closes an exciting circuit for a relay 115 at which contact 116 engages in a starting magnet 117 in the trunk finder TF^2 (negative pole, 116, 118, 103, brush 121, 117, positive pole). The starting magnet 117 closes at the contact 122, the circuit of the motor 19² and this now moves the brushes of the trunk finder until the brush 121 reaches a disconnected trunk, that is to say, a trunk whose line 118 is not connected with the negative pole. The magnet 117 also remains excited until the brush 123 of the trunk finder TF^2 reaches a line which is not already connected by other trunk finders. The test lines 124 of these connected lines are connected by contacts 125 with the negative pole and an excited magnet 117 will therefore receive current through its contacts 126 over those lines 124 connected with the negative pole. As

soon, however, as the brush 123 reaches a disconnected line, the armature of the magnet 117 falls off and the stopping pawl falls into engagement in the gear wheel of the trunk finder TF^2 and holds the brush fast. At the same time, the motor 19² is cut out at the contact 122. 70

The starting magnet 112 of the second line finder TF^2 , excited in the above described manner, provides for itself at contact 128, a 75 circuit independent of the contact 32 of the stepping relay 28 which extends through the brush 108 and test contacts which are connected through contacts like 58 with the positive pole. As soon as the brush 108 reaches 80 the test contact 101, which is disconnected at the contact 58 from the positive pole, the magnet 112 lets its armature fall off, disconnects at contact 113, the motor 19, opens at contact 114 the circuit of the left exciting 85 winding of the relay 115 and interrupts at a second position its own circuit at the contact 128. The relay 115 lets its armature fall back slowly and there arises therefore an exciting circuit for the relay 130 which extends from 90 the negative pole through 116, 130, 129 to the positive pole. The relay 130 now therefore connects the brushes 133, 134 to the group selector or to the current impulse relay 135 and this relay now receives current 95 which extends from the positive pole through the left winding of 135, contact 136, 131, 133, 52, 51, calling station S, 50, 52, 134, 132, 137, right relay 135 to the negative pole. The relay 135 at its contact 138, closes an exciting circuit independent of the contact 116 100 through the right winding of the release relay 115 and through the resistance 139.

At the moment when the relay 130 is excited, the upper winding of the relay 47 is 105 short-circuited since the negative pole is directly applied at the contact 54 through the contacts 116, 140, brush 141. The relay 47 then lets its armature fall off and the relay 45 now remains excited by means of a current 110 which flows from the negative pole through 146, 140, 141, 55, through the low resistance winding of 45.

From the above description, it is clear that the first and second line finders LF^1 and LF^2 115 are started at the same time through a pair of trunk finders TF^1 and TF^2 and that after this starting operation the trunk finders immediately set themselves on disengaged and unoccupied trunks. In the case that two calls 120 arise simultaneously, the stepping relay 28 closes the contacts 33, 34 as well as the contacts 31, 32 and thereby a further first line finder and simultaneously a further second line finder is started which connect the further calling line to a group selector in the manner described for the finders LF^1 and LF^2 . The arrangement, can of course, also be such that three or more simultaneously 125 calling lines are served by different line find- 130

ers. The described operation of connecting the calling line through 200-point line finders, in every case on account of the high working speed of the line finder, takes place in a small fraction of a second. After its connecting through, a current impulse relay 35 of a group selector GF is excited in the manner described. It was assumed that the calling subscriber desires the number 223. He will, therefore, now operate his dial so that two interruptions of the current flowing through the current impulse relay 135 are caused. At the first interruption, a contact 143 of a short-circuit bridging the change-over relay 144 is removed, so that this relay is excited by a current extending from the negative pole 116, 144, resistance 145 to the positive pole and opens a contact 146 and closes a second contact 147 for the purpose of preparing a circuit for the control magnet 111¹. When the current closing relay 135 now again attracts its armature, it closes at the contact 148, a circuit extending through the magnet 111¹ which extends from the negative pole through 148, line 149, bank contact 150, brush 151, contact 147, magnet 111¹ which corresponds to the magnet 11 (Figure 10) to the positive pole. The motor 109 was already previously connected in through the contact 155 of the relay 115 and as soon as the magnet 111¹ is excited in the manner described, the motor now drives the brushes over the bank contact until the brush 151 reaches a contact 156 which is not connected with the negative pole. Here the magnet 111¹ is deenergized and the stopping pawl controlled by it released to engage in the stopping wheel. The brushes, therefore, remain stationary until a negative potential is connected with the contact 156. This takes place on the occasion of the armature drop of relay 135 which is caused by the second line interruption of the sending of numerical impulses which extends from the negative pole through 157, contact 156, brush 151, contact 147, 111¹ to the positive pole. The stopping pawl now again liberates the brush until the brush 151 reaches the contact 158 which is not connected with the negative pole. On the subsequent armature attraction of relay 135, the magnet 111¹ receives a further current which extends from the negative pole, 148, 158, 144, 111¹ to the positive pole. The brushes 151 to 154 are now released until the brush 151 reaches the contact 159. The brushes are now set on the beginning of the second group of contact sets which lead to the connectors of the second 100 group and there now ensues a pause in the sending of numerical impulses until the change-over relay 144 at contact 143 is continuously short-circuited and is thereby caused to let its armature fall back in order to close at contact 146 a circuit for a slow falling off relay 170 which extends from the negative pole through a resistance 171, 146, shaft contact 161, 170 to the positive pole.

The relay 170 connects in at contact 172, the lower winding of the stepping relay 162 and the latter now closes its contacts 173, 174, 164, 175. Owing to excitation of the two relays 162, 170, the magnet 111¹ is connected through the shaft contact 169, contact 176 of the relay 170, contact 164 of the relay 162 with the brush 152 and in the case that the brush stands on a closing contact 160 connected with the negative pole, that is to say, on the test contact of an engaged line, the excitation of the magnet 111¹ now takes place and this magnet applies itself through its contact 167, shunting the contacts 169, 176 direct on the line 168 which leads through the contact 164 to the brush 152. The brushes are again released and wipe over the contact sets until the brush 152 reaches a contact, for example, 166, which has no connection with the negative pole. The current is then interrupted by means of the magnet 111¹ and the upper winding of the stepping relay 162, which only then was short-circuited at contact 167, receives owing to the removal of this short-circuit, a current which flows from the negative pole through contact 201 of the release relay 203 of the connector, contact 166, brush 152, contact 174, upper winding of relay 162, winding 111¹ to the positive pole. In this circuit, the magnet 111¹ is not excited on account of the high resistance of the upper winding of the relay 162. However, the upper winding of the relay 162 opens contacts 178, 136, 137 and at the same time connects the talking line 179, 180 to the brushes 153, 154 and to the current impulse relay 204 of the connector FS. It should be observed that at the moment of deenergization of the starting and stopping magnet 111¹, the brushes 153, 154 for the purpose of exciting the current impulse relay 204, are bridged over temporarily by a shunt path which extends from the brush 154 through contact 181 of the magnet 111¹, contact 175 of the relay 162, contact 178 of the relay 162, contact 182 of the relay 170 to the relay 3. This shunt path was closed at the moment when the contact of the magnet 111¹ was opened and thus made the lower winding of relay 170 dead. In case after selecting the group, the brushes 151, 154 already stand on a free trunk, that is to say, without hunting operation, there takes place through the closure of the path extending from the magnet 111¹ through contacts 169, 176, 164, brush 152, no excitation of the magnet 111¹ and consequently no excitation of the lower winding of relay 170 through the contact 183 of the electromagnet 111¹. The upper winding of relay 170 is short-circuited by closure of the contact 173 of the relay 162 so that the relay 170 lets its armature again fall off and at contact 182 temporarily bridges over the brushes 153, 154 through a path which extends from the brush 154 through contacts 181, 175, 178, 182 to the brush 153.

By this means the current impulse relay 204 of the group selector is excited and thus interrupts at contact 205, the circuit of the release relay 203 which extends from the negative pole through 205, 203, resistance 206 to the positive pole. The relay 203 closes a contact 201 and a current then flows through the upper winding of the stepping relay 162 in the group selector which flows from the negative pole through 201, test line 207, test contact, test brush 152, contact 174, upper winding of relay 162, winding of electromagnet 111¹ to the positive pole. On account of the high resistance of the upper winding of relay 162 this relay only is effected, not however, the electromagnet 111¹. The relay 162 opens at contact 178, the above described bridge for the brushes 153, 154 and connects the calling line through to the contacts 185, 186 to the current impulse relay 204. The current impulse relay 138 is cut off at the contacts 136, 137 so that the relays 115, 144 are deenergized. The dissolution of the connection which would otherwise take place on account of the deenergization of the release relay 115, is however, prevented by the contact 175¹ of the stepping relay 162 which holds the through connecting relay 130 excited by means of a current which extends from the negative pole through 175¹, 130, 129 to the positive pole. The calling subscriber is now connected with the connector or final selector FS and since he wishes to make a connection with the second tens group, he causes by his dial two interruptions of the current flowing through the relay 204. At the first interruption, a short-circuit bridging over the relay 209 is opened at contact 208 so that this relay is excited by a current extending from the negative pole through contact 201, relay 209, resistance 210 to the positive pole.

On the subsequent attraction of the armature of the relay 204, the magnet 211 which corresponds to the magnet 11, Figure 1, receives a current impulse which flows from the negative pole through 205, 208, contact 212, relay contact 213, bank contact 214, brush 215, contact 216, magnet 211 to the positive pole. Through this the stopping pawl is withdrawn from the stopping wheel of the brush carrier and the motor 209 which was already previously switched in through the contact 217 of the release relay 203, now whirls the brushes 215, 216, 217, 218, 219 further up to a contact 220 which has no connection with the negative pole. On the next interruption which is caused by the impulse transmitter, the control magnet 211 receives a current impulse which flows from the negative pole through 201, 224, contact 225, bank contact 220, brush 215, armature 216 of the relay 226, 211 to the positive pole and the brushes are now rotated further until they reach the contact 221 which is in connection with the negative pole. At this moment the

control magnet 211 allows the stopping pawl to catch in the stopping wheel so that the brushes are held. On the closing of the line at the numerical switch falling on the line interruption, the magnet 211 receives a further current impulse which flows from the negative pole through 210, 208, 212, 213, bank contact 221, brush 215, contact 216, 211 to the positive pole and the brushes 215 to 219 are now driven further by the motor until the brush 215 reaches the next intermediate contact 223 not connected with the negative pole. The brushes are now set on the second tens group and a pause ensues in the sending of numerical impulses in which the relay 209¹ closes at the contact 228 a circuit for the receiving relay 226 which extends from the negative pole through 228, 229, of the shaft switch, upper winding of relay 226 to the positive pole. Relay 226 is excited and closes at contact 230 a circuit for itself which extends through contact 231 and 201 to the negative pole. The lines leading from the current impulse relay 204 to the control bank contacts for the group selector, are opened at the contacts 213, 225 and the units line 232 is connected through contact 233 with a relay 234. When the calling subscriber now sends in the three numerical current impulses, the first control current impulse flows from the negative pole through contact 201, 224, 232, 233, winding of relay 234, line 235, contact 236, brush 216, contact 237 which was closed by the excitation of the relay 226, magnet 211 to the positive pole. The relay 234 short-circuits its lower winding and then a current flows through the contact 238 which excites the magnet 211. The brushes are hereby caused to move to the next switch contact set where the brush 216 rests on the bank contact set 240. As soon now as the armature of the relay 204 is attracted and thus opens the contact 224, the relay 234 is deenergized by opening of the holding winding of this relay at contact 241 on the second interruption of the line and closure of the contact 224 caused by the numerical switch the control magnet 211 is excited by a current which extends from the negative pole, through 201, 224, 233, lower winding of relay 234, control contact 250, brush 216, contact 237, magnet 211 to the positive pole. The excitation takes place immediately the lower winding of the relay 234 is short-circuited at contact 238 and the brushes now travel to the contact set on which the desired line number 223 is connected.

During the sending of units current impulses, the contact 251 of the change-over relay 209 is closed and a relay 253 is inserted at contact 252 which prepares a test circuit for the relay 254 at contact 255 and at contact 256 an engaged signal circuit. After the sending of the units current impulses, the change-over relay 291 is deenergized by

a continued short-circuit through the contact 208 and the negative pole is connected through contact 228, contact 255 of the slowly falling off relay 253 to the test relay 254. If the desired line is free, the test relay 254 is excited by a current flowing through the brush 217, test line 260 which corresponds to a test line 260', Figure 2, cut-off relay of the desired line which corresponds to the cut-off relay 23, Figure 2, and the test relay opens at contact 251 the engaged signal circuit, at 263 short-circuits a part of its winding for the purpose of making the desired line engaged, connects by the contacts 264, 265 the talking lines 266, 267 to the desired line and closes at contact 268 the circuit of a ringing current relay 269 which is now excited by current interruptions flowing through the interrupter 270 at predetermined time intervals. At the first moment a ringing current flows from the ringing current machine 272 through resistance 273, contact 274, contact 275, 265, brush 219, to the desired subscriber station and then back through the brush 218, contact 265, line 267, lower relay winding of a relay 276 to earth. The wanted subscriber now receives ringing current impulses until he takes down his receiver. There flows then either an amplified alternating current from the ringing current machine 272 or from the exchange battery 278, through contact 279, through the call station and through the lower winding of relay 276 and this relay is then excited. At the contact 231 the relay 276 opens the holding circuit of the relay 226; at the contacts 279, 280 it makes the talking current circuit between the calling and called subscribers and at contact 275 it disconnects the ringing current machine from the wanted line.

The subscribers can now carry on their conversation. If the called subscriber hangs up his receiver at the end of the conversation, the relay 276 is again deenergized and at contact 282 a short-circuit is made bridging over the release relay 203 which extends from the positive pole through contact 283 of the shaft switch 284, contact 285 of the relay 226, contact 280. The release relay 203 lets its armature fall back and closes at contact 286, a circuit for the control magnet 211 which extends through the contact 287. Through the contacts 286, 288 at the same time, the motor 209 is switched in. The control magnet 211 withdraws the stopping pawl from the toothed wheel in order to release the brushes and these are now rotated by the motor 209 into the normal position where they are again stopped by deenergization of the control magnet 211. The deenergization of the control magnet 211 is effected by the fact that the cam disc 290 on the switch shaft, on reaching the normal position of the brushes, lets the spring of contact 287 or the spring of contact 288 fall into a notch. By this open-

ing of the contacts 287, 288 the control magnet and the motor 209 are deenergized. The maintaining circuit of the relay 253 was already interrupted on the excitation of the test relay 254 at contact 262. The test relay 254 at the end of the connection loses its current through the opening of the contact 201 of the release relay 203. The contacts 283, 229 of the shaft switch 284, are opened as soon as the switch shaft comes back into its normal position. All parts of the connector FS as far as the current impulse relay 204, have now returned to their position of rest. When the calling subscriber hangs up his receiver, the release relay 203 is short-circuited on a path independent of the already described short-circuit path. In case the called subscriber has not yet hung up his receiver, by this means the release or the return of the connector into the normal position takes place in the manner already described.

The return of the group selector GS is initiated by the going off of the negative pole from the line 207 at the contact 201. By this means the current flowing through the top winding of the relay 174 is interrupted so that this relay dies down and closes its contacts 178, 136, 137, 190 controlled in its second switching stage. Through the contact 190 the control magnet 111¹ is inserted in a circuit which extends from the negative pole through contact 191 of the release relay 115, cam disc contact 192, 190, 111¹ to the positive pole. The control magnet 111¹ connects in at contact 194, the motor 109 which now turns the brushes of the group selector into the normal position. As soon as this normal position is reached the spring of contact 291 falls into a notch of cam disc 195, whereby the circuit of the control magnet 111¹ is opened and hereby the stopping pawl of the selector is caused to engage in the toothed wheel of the brush shaft and to stop it. By the deenergization of the magnet 111¹, at the same time the motor 109 is disconnected at the contact 194. The relay 174 removes at contact 175¹ the short-circuit of the right winding of relay 170 and this relay is then again excited by a current flowing from the positive pole through 171, 146, 161. The left winding of the relay 170 also receives during the returning of the brushes or during the further movement of the same into the normal position, a current flowing through the contact 183 of the control magnet 111¹. During the contact 172 of the relay 170, the lower winding of the relay 174 is inserted and by this means the contact 175¹ of the first switching stage of the relay 174 is closed. As soon, however, as the group selector reaches its normal position, the left winding of the relay 170 is disconnected at the contact 183 and since the right winding of the relay 170 is short-circuited by the contact 175¹, the relay 170 lets its armature

fall off whereby the lower winding of the relay 174 is finally disconnected. The negative pole is thereby disconnected from the relay 130 of the second line-finder LF² and the relay 45 of the first line-finder LF¹. These relays now let their armatures fall off. The brushes of the first and second line-finders remain in the positions they have taken up until they are again moved for the purpose of making connections through other bank contacts. They can even make new connections without moving their brushes.

In case the called line after the setting of the brushes of the connector is found engaged, a current flows from the engaged tone device 263, through contacts 298, 261, 256, winding 297 of the current impulse relay 204 and by this means there are produced in the coils of the relay 204, busy tones which indicate to the calling subscriber that the wanted line is engaged. The calling subscriber then hangs up his receiver and thus causes the short-circuiting of the release relay 203 and thus initiates the already described operation for the dissolution of the connection.

I claim:—

1. In a telephone system, a plurality of telephone lines, a plurality of bank contacts in which said lines terminate, brushes for wiping over said bank contacts, means controlled over one of said lines for causing said brushes to move at a high rate of speed to seize said line, and means effective when said brushes fail to seize the said line during a first attempt for causing said brushes to make a second attempt to seize said line but at a lower rate of speed.

2. In a telephone system, a plurality of telephone lines, a plurality of bank contacts in which said lines terminate, a brush set for wiping over said contacts, a spring normally tensioned and tending to drive said brushes over said bank contacts, means controlled over one of said lines for releasing said brushes to seize said one of said lines, means effective when said brushes accidentally pass by said line for causing said spring to be retensioned but to a lower degree whereby said brushes are caused to make a second attempt to seize the calling line at a lower rate of speed.

3. In a telephone system, a plurality of bank contacts in which said lines terminate, means for designating a particular set of bank contacts, a set of brushes for wiping over said contacts, means for driving said brushes until said designated contact set is reached, means for arresting said brushes on said designated set, and means effective when said brushes fail to be so arrested for releasing said arresting means to cause said brushes to be again moved at a different rate of speed in a second attempt to stop on said designated set.

4. In a telephone system, a plurality of telephone lines, a plurality of bank contacts

in which said lines terminate, brushes for wiping over said contacts, a spring for rotating said brushes, means comprising a toothed wheel and an electromagnetically controlled stopping pawl for stopping said brushes when they reach a designated set of contacts, a stopping member for stopping the brushes in their normal positions, a member for disengaging the stopping member from the brushes and for causing said brushes to be held in their normal positions by said stopping pawl alone, said disengaging member being arranged to move the stopping member from its stopping position and to allow said stopping member to return to its stopping position in a period of time less than that required for the movement of said brushes from and back to their normal position.

5. In a telephone system, calling lines, a plurality of finder switches adapted to be automatically operated in response to the initiation of a call on one of said lines, said finders adapted to act in tandem relation in extending the calling line, a preselecting trunk finder switch associated with each of said line finders, means effective when the line finder associated with a preselected trunk fails to reach the calling line within a given time interval to cause said trunk finder to start another line finder, said last mentioned means comprising a multi-position timing switch.

6. A telephone system according to claim 5 in which the timing switch also effects an intermittent connection of ringing current to the called line.

7. In a telephone system, a calling line, a called line, a plurality of line finder switches adapted to act in tandem relation for extending the calling line, a step-by-step timing switch associated with said line finders for automatically starting a second line finder when a first line finder fails to reach the calling line within a predetermined interval, a ringing cut-off and through connecting relay for completing connection between the calling and called lines, and means controlled by said timing switch for applying ringing current to the called line through the contacts of said relay.

8. A switch for automatic telephone systems having a self-contained power drive, a contact bank, a brush set cooperating with the said bank, said brushes adapted to travel in a continuous motion over said bank and means for positively arresting said brushes on any set of contacts comprising an electromagnetically operated armature, a detent carried by said armature and adjustable thereon, and means for adjusting said contact bank with respect to said brush set.

9. In a telephone system, a plurality of telephone lines, each line comprising talking conductors and a test conductor, a plurality of corresponding bank contacts in which said lines terminate, the test contacts having

a longer wiping surface than the talking contacts, a set of brushes for wiping over said contacts, a spring motor for each set of brushes for rotating the same, said brushes adapted to be positively arrested on a designated set of contacts by an electromechanically controlled detent.

10. In a telephone system, a plurality of telephone lines, a plurality of switches for 10 extending said lines, said switches having groups of contacts in which said lines terminate, means responsive to the transmission over said line of selecting impulses for causing the brushes of a selected switch to 15 traverse one portion of a contact group in response to the opening of the line, and to traverse the remaining portion of the group of the closing line.

11. In a telephone system, a plurality of 20 telephone lines, a plurality of sets of bank contacts in which said lines terminate, said contacts comprising talking contacts and group designating contacts, brushes for wiping over said contacts, means for marking 25 a selected set of contacts on which said brushes are to be arrested, means responsive to the reception of one group of selecting impulses for releasing said brushes for rotation to cause said brushes to execute in a con- 30 tinuous motion long steps over said contacts, an electromagnet adapted to be energized by impulses passing through the bank contacts, means responsive to the reception of group selecting impulses for applying po- 35 tential alternately to succeeding group designating contacts, means responsive to the reception of another group of impulses for releasing said brushes to cause them to execute short steps, and means responsive to 40 the termination of said other group of im- pulses for positively arresting said brushes on the desired set of talking contacts.

12. In a telephone system, calling lines arranged in groups, a plurality of finder 45 switches associated with each group of lines, said finders adapted to operate in tandem relation to extend a calling line, a plurality of trunk finders associated with said finder switches, means controlled by one of said 50 trunk finders and responsive to the initiation of a call on one of said lines for starting an idle one of said line finders, means effec- 55 tive when another call is initiated on a line in the same group as the first calling line for starting another set of line finders to seek the second calling line.

13. In a telephone system, a plurality of calling lines arranged in groups, a plurality of finder switches for each group arranged 60 to be operated in tandem to extend the calling line, a plurality of preselecting trunk finders and a multi-positioned timing switch associated with said trunk finders for automatically starting a second set of line finders 65 when the first set of line finders fails to con-

nect with the calling line within a predetermined time interval.

14. In a high-speed automatic telephone system, means for establishing a talking connection, said means comprising a plurality of line finders in tandem relation, and a spring motor individual to each of said line finders.

15. In a high-speed automatic telephone system, means for establishing a conversational connection comprising a plurality of line finders in tandem relation, means for starting said finders substantially simultaneously upon the initiation of a call, and a spring motor individual to each of said line finders.

16. In a telephone system, calling lines, called lines, trunk lines leading from said calling lines toward the said called lines, a plurality of sets of bank contacts in which said trunk lines terminate, a brush set for wiping over said contacts, a controlling magnet for said brush set whose armature responds with high speed to the absence of potential on a designated set of bank contacts, said electromagnet having a nickel iron core for accelerating the deenergization thereof.

In testimony whereof I have hereunto affixed my signature.

FRITZ ALDENDORFF.
